UNITED STATES PATENT OFFICE

2,076,300

STRAIGHTEDGE

Arthur J. La Croix, Southbridge, Mass., assignor
to Hyde Manufacturing Company, South-
bridge, Mass., a corporation of Massachusetts

Application July 18, 1935, Serial No. 32,027

7 Claims. (Cl. 33—107)

My invention relates more especially to a wall paper trimmer's straightedge and has to do with the metallic binding strips and the manner of securing the same in place so as to provide a smooth uninterrupted outer surface for the trimming tool or paper cutter during its travel longitudinally of the straightedge.

5 Straightedges made of wood require the longitudinal edges to be provided with metallic protective elements, generally brass strips of channel formation and adapted to extend from end to end of the straightedge, with the side of one of the channel strips adapted to provide a track-way for the guide member of the paper trimming tool.

10 The invention has for its object the provision of means so associated with the metal edging or binding strips that the fastening means will be entirely located on the straightedge side of the binding strip and will effect holding or fastening relation with the body of the straightedge without fracturing the latter and at the same time will maintain the proper holding relation regardless of any shrinking or warping of the body of the straightedge.

15 A further object of the invention is to provide a construction which may be easily made and assembled and the metal edging strips securely held in place against accidental removal or from becoming loose.

20 The aforementioned objects and advantages, as well as other advantages inherent in the construction, will be readily comprehended from the following detailed description of the accompanying drawing, wherein:—

25 Figure 1 is a sectional perspective view of a straightedge embodying my invention.

Figure 2 is a longitudinal sectional view taken substantially along the line 2—2 of Figure 1, looking in the direction of the arrows.

30 Figure 3 is a detail perspective view of one of the metal edging fastening means.

Figure 4 is a perspective view of a modified form of a screw-holding clip or plate.

35 Figure 5 is a perspective view of another modified form of clip or plate.

40 Straightedges made of wood, or a suitable fibre, require the longitudinal edges to be provided with a metallic protective element or strip, which usually is of channel or angle formation. These metallic strips have heretofore generally been secured to the body of the straightedge by means of screws driven through spaced apart holes in the strips along the longitudinal sides of the 45 straightedge.

In practice it has been found that the screws would become more or less loose and have a tendency to "back-out" or unscrew; a condition not always readily noticeable. As a result the trimmer blade would make contact with the slightly 5 protruding head of the screw and consequently damage the blade. Damage and dulling of the blade also has resulted from small metal burrs on the screw-heads or in the countersink for the screw-heads in the metal strips and produced by 10 the action of a screw-driver.

The invention contemplates a construction wherein the objectionable conditions just enumerated will not be present; and in the specific embodiment, the body portion 5 of the straightedge is made of laminated wood to provide a straightedge of desired width and length. The upper surface of the body portion 5 slightly removed from one of the longitudinal edges is longitudinally grooved at 6 to provide clearance for 15 the guide element on the trimmer.

10 The longitudinal edges of the straightedge are provided with metallic channel members 7, 7, disposed throughout the entire length of the straightedge.

15 The metal channel members are adapted to receive the longitudinal edges of the main body 5 with the sides of the channel members arranged in lapping relation with the upper and the lower faces of the main body portion 5.

20 One of the sides of each channel member is shown of greater width than the other (although both sides may be of equal width) and the wide side preferably overlaps the upper face of the straightedge; and hence the wide side of 25 channel member 7 will overhang a portion of the groove 6 in the body 5, and enable it to act as a guide when a trimming tool is used.

Both sides of the channel members, adjacent the base of the channel, are provided with a 30 slot or small groove 8 which preferably extends throughout the length of each side of the channel members 7, as shown in Figure 2.

35 The grooves 8, 8 are adapted to receive the longitudinal edges of the holding plates or washers 9, shown in detail in Figure 3. The plates or washers 9, intermediate of the ends, are apertured for passage of the threaded portion of the screws 10 therethrough and permit free rotary movement of the screws. The apertures in the 40 plates or washers 9 are countersunk as shown at 45 50 55 60 65 70 75 80 85 90 95 100 105 110 115 120 125 130 135 140 145 150 155 160 165 170 175 180 185 190 195 200 205 210 215 washer in which the head of the screw will seat so as to be flush with the outer side of the washer while giving the screw free play.

The screw 10 is preferably provided with a quick 5 thread to induce it to screw into the wood body 5 of the straightedge when the head of the screw is subjected to pressure or blows; such rotating or screwing movement being possible by reason of the loose fit between the screw and the washer.

10 It is apparent that with the longitudinal edges of the plate or washer 9 arranged in the slideway produced by the opposing grooves 8, 8, the metal strips 7 will be secured to the longitudinal edges of the main body of the straightedge; a suitable 15 number of the composite holding elements 9—10 being used, spaced apart longitudinally of the straightedge.

In practice, the composite holding elements or fastening means 9—10 are first applied to the 20 longitudinal edges of the main body of the straightedge by driving the screws 10 into the fibre or wood to such an extent that the plate or washer 9 will be held against rotation on the screw, namely to the point where the cupped countersunk portion 11 will engage the body 5 of the straightedge and hold the washer 9 in position with its longitudinal edges extending parallel with the longitudinal edges of the body 5, while at the same time permitting sufficient play of the washer 25 to enable it to freely enter the slots or grooves 8, 8 from one end of the channel binding strips 7.

The washers 9 are preferably made slightly wider than the thickness of the main body 5 of the straightedge so as to permit the longitudinal 30 edges of the washers to extend into the slots or grooves 8, 8 at opposite sides of the channel binding strips 7 as shown in Figure 1.

After the fastening means, consisting of elements 9 and 10 have been applied to the main 40 body 5 as above stated, the binding strips are then endwise applied to the straightedge with the sides of the channel strips disposed toward the body 5 and the ends of the grooves 8, 8 arranged to register with the longitudinal sides of 45 the plates or washers 9. The binding strips 7 are slid lengthwise of the body 5, in interlocking relation with each plate or washer 9, until the ends of the binding strips are flush with the ends of the body portion 5. The strips are then subjected 50 to slight blows or pressure, at points substantially coincident with the washer carrying screws, which will completely drive the screws into the body portion 5 and firmly hold the metal edging in place against accidental movement; the cupped 55 portions 11 of the washers becoming embedded in the body portion 5 as shown.

In order to obviate any possibility of the edging or binding strips 7 moving lengthwise of the straightedges through some improper handling, I 60 prefer to employ at each end of the straightedge the type of washer or clip 14 shown in Figure 4. This clip or washer 14, which is preferably made of tempered steel, has one end slightly bent and ground to a chisel edge as at 15; this edge being 65 disposed toward the opposite side of the clip provided with the cupped or screw-head received portion 11. That is to say, the bent sharp edge 15 is intended to be disposed toward the base of the channel strip 7; and as these clips are preferably 70 tempered the sharp edge 15 will bite into the brass channel.

With this construction accidental travel or movement of the channel strips lengthwise of the straightedge is made impossible.

75 In practice, clips like that heretofore described

and shown in Figure 3 are applied intermediate of the ends of the straightedge, either by using the ordinary wood-screw or a quick-thread screw, and a clip like 14 is secured adjacent one end of the straightedge; these clips being secured to the body of the straightedge so as to permit the longitudinal edges of the clips to enter the grooves or slots 8 in the channels. The channel is driven along the edge of the body of the straightedge toward the opposite end which is then provided with a clip like that shown in Figure 4 and the channel 10 15 20 25 30 35 40 45 50 What I claim is:—

1. A straightedge of the character described comprising a fibrous body portion; imperforate metal strips disposed along the longitudinal edges; fibre penetrating elements arranged at preselected points lengthwise of the body portion; and means intermediate of the metal strips and the outer ends of the elements whereby holding relation between the strips and said elements is effected.
2. A straightedge of the character described comprising a wood body; imperforate channel metal strips disposed along the longitudinal sides; screw carrying elements arranged within the channel strips and in gripping relation therewith whereby the metal strips are secured to the sides of the body of the straightedge; and a wood screw disposed through each element and screwed into the wood body.
3. A straightedge of the character described comprising a main body portion; imperforate metal channel strips extending throughout the longitudinal sides of the body portion, the inner side walls of the channel having opposing grooves; screw carrying washers whose edges fit into said grooves; and body portion penetrating screws disposed through the washers.
4. A straightedge of the character described comprising a fibrous body portion; channel strips arranged along the longitudinal edges of the body portion; body portion penetrating elements; and rigid means adapted to effect interengaging relation with the inner surfaces of said strips and arranged in holding engagement with said elements.

5. A straightedge of the character described comprising a main body portion; imperforate metal channel strips extending lengthwise of the longitudinal sides of the body portion, the inner side walls of the channels adjacent the base having opposing grooves; apertured metal washers of width substantially equal to the distance between the bottoms of the opposing grooves arranged with their longitudinal edges disposed in said grooves, said washers being arranged in binding engagement with the channel; and a screw disposed through the aperture in each washer and screwed into the body portion.

6. A straightedge of the character described comprising a fibrous body; imperforate metal strips disposed along the longitudinal sides of the body; body penetrating elements arranged at preselected points lengthwise of the body; and means secured to the body penetrating elements adapted to effect a frictional inter-engaging relation with the strips and thereby hold the latter in place.

7. A straightedge of the character described comprising a body portion; metal strips arranged along the longitudinal edges of the body portion; body penetrating elements inserted into the longitudinal edges of the body portion at spaced apart points; and means secured to each element and arranged in holding relation with the inner faces of the metal strips to thereby secure the strips on the longitudinal edges of the body portion.

ARTHUR J. LA CROIX. 35
